UNITED STATES PATENT OFFICE.

OSCAR HAMMERSTEIN, OF NEW YORK, N. Y.

FIRE-EXTINGUISHING DEVICE.

No. 821,938.

Specification of Letters Patent.

Patented May 29, 1906.

Application filed January 11, 1904. Serial No. 188,453.

To all whom it may concern:

Be it known that I, OSCAR HAMMERSTEIN, a citizen of the United States, and a resident of the borough of Manhattan, city, county, 5 and State of New York, have invented certain new and useful Improvements in Fire-Extinguishing Devices, of which the following is a specification.

My invention relates to fire-extinguishing 10 devices, and especially to such as are intended for use in buildings—for instance, theaters.

The object of my invention is to provide a 15 device of the above-indicated class which will be very efficient, which can be controlled instantaneously from a readily-accessible point, and which will not depend for its working upon the running of any motor or other machinery liable to fail or to be abandoned in case of a fire.

20 The invention will be fully described hereinafter and the features of novelty pointed out in the appended claims.

Reference is to be had to the accompanying drawings, in which—

25 Figure 1 is an elevation of my improved fire-extinguishing device with parts in section. Fig. 2 is a plan thereof, and Fig. 3 is partly a front elevation of the stage and partly a sectional elevation.

30 At suitable points at the upper portion of the building—for instance, upon the roof—I provide one or more tanks A, and preferably separate tanks are provided for each side of the building. In the example shown there

35 are two tanks at each side. From each of the tanks a wide outlet-pipe B extends at the bottom, and preferably these outlet-pipes connect the tanks on the same side of the building with each other. From a central

40 point of this outlet or connecting pipe B a branch pipe C leads to a head D, it being understood that there is such a head at each side of the building. The two heads D are connected by a series of perforated pipes E, 45 preferably parallel. Each branch pipe C contains a controlling-valve F, from which any suitable operating mechanism extends to a point in proximity to the stage-floor, so that attendants stationed at these points may

50 upon an instant's notice open the valves F. The operating mechanism may consist of a crank-arm F', connected with the valve-plug rigidly and having a loose connection with an actuating-rod G, movable up and down in guides G'. It will be understood that when the valves

F are opened water from the tanks A will pass through the branch pipes C to the heads D and will issue in the form of jets from the perforated pipes E. The perforations may 60 be directed downwardly, so that the jets will be parallel, or the perforations may be slightly oblique, so as to cause the jets to cross each other. Instead of perforating the pipes E, I may make them with narrow slits. It will 65 be understood that the pipes E, perforated or otherwise apertured, are located at a suitable height above the scenery M, especially scenery suspended from the gridiron N, known as the "rigging-loft," so that these pipes will be 70 practically invisible to the audience and yet efficiently disposed to thoroughly sprinkle and inundate the whole stage (particularly scenery) in case of an emergency. I may also combine the rigging-loft and the pipes E 75 into one structure—that is, I may employ the pipes E as a rigging-loft, thus dispensing with the separate floor or gridiron N of Figs. 1 and 3.

The tanks A are filled in any suitable manner, and I have not deemed it necessary to illustrate any particular mechanism for this purpose. It is obvious that the efficiency of the device will depend on the amount of water stored in the tanks, and it therefore is 80 eminently desirable that the condition of the tanks should be readily ascertainable at any time. As the tanks are located in a rather inaccessible place, gage-glasses or like appliances would not be convenient, and I prefer 85 to provide an indicating device at about the same level as the operating device, so that the attendant (fireman) may readily ascertain how much water the tanks contain without leaving his post. The indicating device 90 shown consists of a float H, the stem of which, H', has guided movement in the top of the tank and is connected with a wire or rod I, guided over pulleys J and connected with a movable member or pointer K, arranged to 95 indicate on a stationary scale L. Inasmuch as each pipe B in the construction shown connects two of the tanks A, it will be clear that only one indicating device will be required for the two connected tanks. 100 105

It will be understood that while I have described the arrangement of tanks at the sides of the building with the apertured pipes running crosswise of the stage, different arrangements may be employed, if desired. I prefer 110 to provide two heads D, each connected with a water-supply and with the apertured

pipes E, for the reason that in practice the pipes E will be rather long, and if water were supplied to them from one end only the pressure would fall considerably toward the unconnected ends of said pipes. However, with small stages it might be feasible and practicable to dispense with the water-supply at one end, in which case one of the heads D might be dispensed with or at least be without any connection to a water-supply device.

I claim as my invention and desire to secure by Letters Patent—

1. A fire-extinguishing device comprising heads, apertured pipes connecting said heads, a plurality of tanks for each head, pipes connecting the tanks belonging to each head, a branch pipe extending from each connecting-pipe to the corresponding head, a valve in said branch pipe, an actuating device for

said valve, and a device for indicating the amount of water in said tanks, said indicating device being located at about the same level as the handle of the actuating device.

2. A fire-extinguishing device comprising heads, apertured pipes connecting said heads, a plurality of tanks for each head, pipes connecting the tanks belonging to each head, a branch pipe extending from each connecting-pipe to the corresponding head, a valve in said branch pipe, and an actuating device for said valve.

In testimony whereof I have hereunto set my hand in the presence of two subscribing witnesses.

OSCAR HAMMERSTEIN.
